UNITED STATES PATENT OFFICE.

ALFRED R. WOOD, OF BRIDGEPORT, CONNECTICUT, ASSIGNOR TO THE SINGER MANUFACTURING COMPANY, OF ELIZABETH, NEW JERSEY, A CORPORATION OF NEW JERSEY.

THREAD-CUTTING MECHANISM FOR SEWING MACHINES.

Application filed May 4, 1925. Serial No. 27,627.

This invention relates to thread-cutting mechanisms for sewing machines and more particularly to mechanisms for severing and holding the under thread in a two-thread 5 sewing machine.

The invention has for an object to so construct the mechanism in question as to avoid down pulls on the under thread leading to the last stitch, which pulls tend to draw or 10 distort the work.

A further object of the invention is to provide an under-thread cutting and holding mechanism of simplified construction which is particularly adapted for use in 15 machines for sewing groups of stitches or buttonholes in thin and easily distorted material.

To the attainment of the ends in view, means are provided for first gripping the 20 under-thread below the work, thence severing the thread between the gripper and the work and thereafter moving the gripper to pull off and supply sufficient slack under-thread to permit the first needle-loop to draw 25 the under-thread up to the work. The severing means are preferably in the form of a shear, and means are preferably provided for releasing the gripped thread-end after the initial stitches have been formed.

In the accompanying drawings, Fig. 1 is a 30 side elevation, partly in section, of a button-hole sewing machine embodying the invention. Fig. 2 is a bottom plan view of the machine. Fig. 3 is a top plan view of the bracket-arm of the machine. Fig. 4 is a 35 transverse vertical section through the machine on the line 4—4, Fig. 1. Fig. 5 is a bottom plan view of the thread-cutting and gripping devices in their initial position occupied during the sewing and as the machine comes to rest; the gripper jaws being open. Fig. 6 is a similar view showing the 40 open gripper jaws moved to embrace the under-thread and about to be closed thereon. Fig. 7 shows the gripper jaws moved to 45 extreme position after gripping and severing the under-thread, to pull off a supply of such thread for the starting of the next sewing operation. Fig. 8 shows the gripper jaws returned closed to initial position, the 50 showing of the thread being omitted; such jaws being subsequently opened to release the under-thread when the initial stitches of the next sewing operation have been formed.

Fig. 9 is a bottom plan view of the thread-gripper elements only. Fig. 10 is a transverse section through the machine bed on the line 10—10, Fig. 5. Fig. 11 is a similar view on the line 11—11, Fig. 6. Fig. 12 is a similar view at a slightly later stage of the 55 operation of the mechanism, showing the severing of the thread by the cutter. Fig. 13 is a similar view on the line 13—13, Fig. 7. Fig. 14 is a similar view on the line 14—14, Fig. 8, with the slack under-thread end shown held by the gripper. Fig. 15 is a perspective view of the longitudinal slide-plate of the work-holder, and Fig. 16 is a perspective view of the cross-slide plate of the work-holder. 60

For the purposes of the present disclosure the invention is described as embodied in an automatic straight buttonhole sewing machine constructed substantially in accordance with the disclosure of the copending application of E. B. Allen, Serial No. 487,001, filed July 23, 1921. This machine has the usual bed 1, standard 2, overhanging arm 3 and head 4. The stitch-forming mechanism comprises the reciprocating and laterally 65 vibratory needle-bar 5 carrying the eye-pointed needle 6. The needle-bar 5 is journaled in the swinging gate 7 which is mounted on the pivot pins 8 and derives its vibratory movement in any suitable manner from the main sewing shaft 9. For example, the gate 7 may be connected by means of the link 10 to the slotted arm 11 which is fulcrumed at 12 on the bracket-arm 3 and is 70 connected by the link 13 to the crank-pin 14 mounted on the radially adjustable slide 15 carried by the rotary guide-head 16 on the vertical shaft 17. The shaft 17 receives semi-rotational impulses through the train 75 of gears 18 from the shaft 19 which carries the star-wheel 20 with which mesh the pins 21, Fig. 3, carried by the hub of the bevel gear 22 mounted on the bearing pin 23 and receiving its motion from the bevel pinion 24 carried by the sewing shaft 9. The gear 22 is driven at half the speed of the shaft 9 and the gearing 18 is of such ratio that the shaft 17 is given a semi-rotation for each impulse of the star-wheel 20 received from one of the pins 21. The needle-bar is reciprocated by means of the usual crank 25 and link connection 26 with the sewing shaft 9. 80

The under thread *b* is carried by the bob- 85

90

95

100

105

The under thread *b* is carried by the bob-

bin element 27 of the usual shuttle (not shown) which is mounted in the race 28 and driven by means of the lower oscillatory shuttle-shaft 29 having the usual driving connections with the crank 30 on the main-shaft 9; such connections including the crank-arm 31 and an intermediate rock-lever 32 and pitman 33.

The work is held by the usual work-clamp comprising the longitudinal slide-plate 34 on a lateral extension 35 of which, Figs. 1 and 2, is pivotally mounted at 36 the upper clamp-lever 37 carrying the clamping foot 38. The longitudinal slide-plate is mounted in the slideways 39, Figs. 15 and 16, in the cross slide-plate 40 which slides crosswise of the bed 1 in the ways 41, Fig. 1. The longitudinal slide-plate 34 is actuated by means of the usual link 42, Fig. 2, and lever 43 having a follower 44 entering the longitudinal-feed cam-groove 45 in the feed-wheel 46. The cross-slide plate is actuated by the lever 47 which is fulcrumed at 48 on the bed 1 and has a follower 49 entering the lateral-feed cam-groove 50 in the feed-wheel 46. The feed-wheel is mounted on the vertical shaft 51 which is connected to be driven through a suitable system of reduction gears 52 from the shaft 19. This wheel is given one revolution per buttonhole producing cycle.

The period of action of the stitch-forming mechanism is controlled by the usual stop-motion device comprising the tight and loose pulleys 53, 54, the belt-shipper 55 and the tilting stop-motion lever 56 carrying the vertically movable spring-pressed stop-plunger 57.

The particular machine chosen for disclosure of an embodiment of the invention is equipped with a control shaft 58 which is disposed transversely of the machine bed and is actuated from a constantly running power-driven pulley 59 through a suitable partial-rotation clutch mechanism including a driven disk 60 carrying two angularly spaced radially slidable clutch-controlling dogs 61, Fig. 1. This mechanism is fully disclosed in the Allen copending application Serial No. 487,001, previously referred to and a detailed description thereof is not believed to be necessary to an understanding of the present improvement. It will suffice to explain that this shaft is automatically given a partial rotation prior to the starting of the stitch-forming mechanism, and a second partial rotation after the stitch-forming mechanism has come to rest. The first partial rotation of the shaft 58 serves to close the work-clamp and start the stitch-forming mechanism, and the second partial rotation of such shaft is conveniently made use of to operate the buttonhole and thread-cutting mechanisms and to open the work-clamp.

The present invention is particularly con-

cerned with the under-thread cutting and holding mechanism. Referring to Figs. 7 to 16 inclusive, it will be seen that there is employed a primary lever 62 which is pivotally mounted at 63 on the under side of the cross slide-plate 40. This lever is formed intermediate its ends with a lengthwise extending slot 64 through which freely passes a screw 65 carried by an actuating slide-bar 66 fitted in a slideway 67, Fig. 1, in the bed 1, beneath the cross slide-plate 40. The primary lever 62 has secured to its free end the spaced rigid and yielding members 68, 69, Fig. 10, constituting one jaw of a thread-gripper. The other jaw of the thread-gripper is constituted by a secondary lever 70 which is pivoted at 71 on the primary lever 62 and is formed at its free end with a blunt edged jaw 72 adapted to enter the space between the rigid and yielding members 68, 69, and grip the thread *b* therebetween. A dished spring washer 73 is provided between the head of the screw 71 and the lever 70 to impose a frictional drag upon the lever 70 in its movements relative to its companion lever 62. The lever 62 is provided with a stop-pin 74 to limit the opening movement of the jaw 72. It will be observed that during the movement of the gripper-jaws from the full-line initial position to dotted-line extreme position, Fig. 2, they pass under the needle-slot 75 in the throat-plate 76 which is carried by the cross slide-plate 40, Fig. 16. During this movement, the sharpened leading edge 77, Fig. 12, of the primary lever 62 engages the sharpened edge 78 of a ledger-blade 79 which is secured to a bar 80, Figs. 10 and 16, mounted on the cross slide-plate 40 and constituting one of the ways 39 for the longitudinal slide-plate 34.

The cutter- and gripper-actuating slide-bar 66 is operated by means of a cam 81, Fig. 2, on the control shaft 58. The cam 81 engages a follower 82 on the lever 83 pivoted at 84 on the under side of the bed 1 and having a forked free end 85 which embraces the vertical pin 86 depending from the slide-bar 66 through a slot 87 in the bed 1. A spring 88 serves to retain the follower 82 continuously in engagement with the cam 81.

In the initial position of the parts, Figs. 5 and 10, at the close of a sewing operation, the jaws 68, 72 are open. When the shaft 58 executes its partial rotation subsequent to sewing, the inclined portion 81' of the cam 81 acts on the lever 83 to shift the slide-bar 66 and carry the jaws 68, 72, across the lead of the under thread *b* which is slightly deflected by the inclined surface or leading edge 89, Fig. 6, around the end of the jaw 72 and slips in between the open jaws 68, 72, as soon as the end of the jaw 72 is carried past said thread.

The secondary lever 70 carries a pin 90

which engages the cam edge 91 on the plate 92 mounted on the slide-bar 66 and closes the jaw 72 upon the thread *b*, such closure taking place during the movement of the jaws between the positions shown in Figs. 11 and 12. As soon as the thread *b* is securely gripped, the length thereof leading to the work is severed by coaction of the edges 77, 78 of the shear-blades 68, 79. The further movement of the jaws 68, 72 to the position shown in Fig. 13 pulls under-thread from the bobbin which is slackened upon the return of the gripper-jaws to initial position, Figs. 8 and 14; such return preferably occurring immediately following the pull-off stroke of the jaws 68, 72 and during the last stage of the partial rotation of the control shaft 58 subsequent to sewing.

When the next sewing operation is started, there is sufficient slack in the under thread *b* to permit the first needle-loop to draw the under thread up to the work. After two or three stitches have been formed, the cam 93, Fig. 2, on the feed-wheel 46 swings the lever 94 and carries the laterally extended free end 95 thereof, Fig. 8, into engagement with the pin 96, on the lever 70, and shifts such lever to open the gripper-jaws and release the under thread. The spring 97, returns the lever 94 to inactive position after the cam 93 passes the latter. By gripping and severing the under thread *b* close to the needle-hole 75, and thereafter pulling off slack under thread for the beginning of the next sewing operation, down-pulls of the under thread leading to the last stitch are avoided. Such down-pulls on the under thread are particularly objectionable when sewing thin work as they distort and pucker the work and tend to draw it into the needle-slot in the throat-plate, as well as causing holes to be cut in the work. The holding of the under-thread end at the beginning of the next sewing operation enables the initial stitches of the buttonhole to be securely and properly set, which result is not secured when the under-thread end is allowed to hang loose. It very often happens that a loose under-thread end is not caught up by the initial needle-loop or loops cast about the bobbin.

The upper clamping foot 38 of the machine is preferably equipped with the usual needle-thread cutter 98, Fig. 1, which may be constructed and operated substantially in accordance with the disclosure of said Allen copending application.

Having thus set forth the nature of the invention, what I claim herein is—

1. The combination with a throat-plate and stitch-forming devices including a reciprocating needle and under-thread mechanism, of means below the throat-plate for gripping the under thread, means for severing the under-thread between the gripping

means and the last stitch, and means for pulling off slack under-thread between the gripping means and the under-thread supply.

2. The combination with a throat-plate and stitch-forming devices including a reciprocating needle and under-thread mechanism, of means below the throat-plate for gripping the under-thread, means for severing the under-thread between the gripping means and the last stitch, and means for moving said thread gripping means after severance of the under-thread to pull a length of slack thread from the under-thread supply.

3. The combination with a throat-plate and stitch-forming devices including a reciprocating needle and under-thread mechanism, an under-thread gripper below the throat-plate, means for closing said gripper upon the under-thread, means for severing the under-thread between said gripper and the last stitch, and means for thereafter imparting to said gripper a to-and-fro pull-off and thread-slackening motion of sufficient amplitude to provide enough slack under-thread to permit the first needle-loop to be drawn up to the work.

4. The combination with a throat-plate, a reciprocating needle and under-thread mechanism, of a stationary ledger-blade below said throat-plate and an under-thread pull-off in the form of a thread-gripper having a cutting edge cooperating with said ledger-blade.

5. The combination with stitch-forming devices of a thread-gripper having coacting jaws movable side-wise across the lead of the thread, one of said jaws having an inclined surface adapted to deflect the thread around the free end of such jaw, thereby permitting the thread to enter between said jaws, and means for closing said jaws upon the thread.

6. Thread cutting and holding mechanism for sewing machines comprising a primary pivoted lever formed with a cutting edge and a thread gripping jaw, a secondary lever fulcrumed on said primary lever and having a gripping jaw mating with said first mentioned gripping jaw, a slide bar connected to move said primary lever, and a cam on said slide bar adapted to be engaged by said secondary lever to effect closure of said jaws.

7. The combination with a throat-plate and stitch-forming devices including a reciprocating needle, a loop-taker and a bobbin, of an under-thread gripper including a pair of jaws movable in a plane parallel to the throat-plate and intermediate the throat-plate and the bobbin, one of said jaws having a cutting edge, a stationary ledger-blade with which said cutting edge cooperates to produce a shear cut, means for closing said jaws on the under-thread, and means

for moving said closed jaws to and beyond the ledger-blade to sever the under-thread and pull off a length of slack under-thread for the beginning of the next sewing operation.

8. The combination with a throat-plate and stitch-forming devices including a reciprocating needle, a loop-taker and a bobbin, of means for gripping the bobbin-

thread between the bobbin and the last 10 stitch, means for severing the gripped bobbin-thread close to the under side of the work, and means for thereafter moving said gripping means to pull off thread from the bobbin.

In testimony whereof, I have signed my name to this specification.

ALFRED R. WOOD.
